COLOR COMPARING INSTRUMENT OR THE LIKE

Astro J. Tuomi, Southbridge, Mass., assignor to American Optical Company, Southbridge, Mass., a voluntary association of Massachusetts

Application July 6, 1954, Serial No. 31,275

Term of patent 14 years

(Cl. D57—1)

Fig. 1

Fig. 3

Fig. 2

Fig. 1 is a rear perspective view of a color comparing instrument, showing my new design;

Fig. 2 is a front elevational view of the color comparing instrument shown in Fig. 1 taken on an enlarged scale; and

Fig. 3 is a top plan view thereof taken on an enlarged scale.

The dominant features of my design reside in the portions shown in full lines in the drawing.

I claim:

The ornamental design for a color comparing instrument or the like, substantially as shown and described.
